UNITED STATES PATENT OFFICE.

MORRIS TEPPER, OF CHICAGO, ILLINOIS.

PERFORATING AND SCORING ATTACHMENT FOR PRINTING PRESSES.

Application filed December 11, 1924. Serial No. 755,271.

To all whom it may concern:

Be it known that I, MORRIS TEPPER, a citizen of the United States, residing at Chicago, in the county of Cook and State of Illinois, have invented new and useful Improvements in Perforating and Scoring Attachments for Printing Presses, of which the following is a specification.

This invention relates to platen printing presses, and more particularly to scoring and perforating appliances therefor, and its object is to provide a novel attachment for this purpose which will be simple in construction and efficient in operation.

In printing presses of the platen type, the platen approaches and recedes from the type form, the inking rollers passing over the latter in a vertical direction while the platen is spaced from the same. Scoring or perforating strips are at times incorporated in the form to serve simultaneously with the printing action, vertical strips of this nature being more frequently employed, such as for the scoring of book covers, folders and the like or the perforating of receipt books, order blanks, etc. While form-retained scoring and perforating strips are efficient for the immediate effect of these operations, they have been found more or less unsatisfactory because of damage incident to their operation. Thus, due to the passage of the inking rollers over the form, a coating of ink is given the scoring or perforating strips as well, whereby they print, as the press closes, where but scoring or perforating is desired; and, due to the prominence of the scoring or perforating strips on the face of the form, the inking rollers—made of a yielding material—become annularly grooved or cut as they ride on the strips, and thus become unfit for any other work.

In order to remedy the situation just related, my invention has for its specific object to associate the novel scoring and perforating element with the platen, whereby it will be outside the path of the inking rollers, thus keeping the strips free of ink and the rollers clear of damaging contact.

A further object of my invention is to apply the novel scoring and perforating element as an attachment to the standard gripper carriage, so that the press will require no alterations or additions to adapt it to the new equipment.

A still further object of the invention is to make it variously adjustable to suit the

conditions of the work and serve for long periods without replacement.

With the above objects in view, and any others which may suggest themselves from the description and claims to follow, attention is directed to the accompanying drawing forming a part of this specification, in which

Figure 1 is a face view—partly broken away—of a press platen, showing the novel appliance in position; 65

Fig. 2 is an edge view; and

Fig. 3 is a detail section on the line 3—3 of Fig. 1. 70

Referring specifically to the drawing, 5 denotes the platen and 6 the gripper carriage of a standard printing press, said carriage being hingedly disposed as shown at 7, and having the usual horizontal slots 8. The form, inking rollers, or other surrounding parts of the press have not been shown; since the present illustration will suffice for those skilled in the art to gain a complete understanding of the invention and its application to the press. 75

The novel appliance comprises mainly a pair of laterally spaced steel bars 9 which are laid on the face of the platen in the manner shown. Each bar is rectangular in cross-section and is outwardly enlarged at the lower end to form a base plate 10, positioned upon the gripper carriage 6. The base plate 10 has a pair of laterally spaced openings registering substantially with the gripper carriage slots 8, the inner opening 11 being round, and the outer 12 vertically elongated. A bolt 13 passes through each opening and through the gripper carriage to receive a nut 14 on the other side of the same, whereby the bars are secured to the gripper carriage. The extended opening 12 is intended to permit variations in the adjustment of the bar before the bolt is tightened. The two bars 9 are thus capable of being adjusted both as to spacing and parallelism. 85

In order that the bars 9 may be rigidly maintained in properly spaced relation at their upper ends, a transverse screw 15 is loosely passed through them thereat, with locking nuts 16 on either side of each bar. With the nuts loosened, the bars may be spaced a predetermined distance, and the adjustment fixed by re-tightening the nuts. The screw 15 may be supplied short as 90 shown, or of a length covering the width of the platen, to suit any spacing adjustment. 105

To the side faces of each bar 9 are secured by screws 17 two steel strips 18 and 19. These project slightly from the visible faces of the strips—as indicated in Fig. 3—the strips 18 being finished with a blunt edge 18^a, and the strips 19 with a saw-toothed edge 19^a.

In operation, the advance of the platen upon the form will carry the appliance along so as to impress the signature with crease lines by the scoring strips 18 and perforation lines by the perforating strips 19, the form being of course built up with wooden "furniture" strips to provide a suitable receiving or backing element for the signature so impressed. The bars 9 may be used with either the scoring strips or perforating strips, alone, as the conditions may demand, and also either singly, in pairs as shown, or 20 in "gangs" for multiple work. When used to score or perforate hinged books in "gangs", the coupling adjustment at the top of the bars 9 will maintain the bars with sufficient rigidity to impress the work accurately and uniformly.

It will be seen that the above appliance provides a simple expedient to accomplish the objects contemplated. The scoring and perforating elements are kept clear of the inking rollers so as not to receive any ink therefrom or affect them in any manner. Such elements are easily removable and interchangeable, and also renewable in case of wear, enabling the appliance to be used 30 and maintained for a long period at trifling expense. Gripper carriage design being standard, the device is applicable to any platen press without occasioning any change in or addition to the same.

I claim:

1. A scoring and perforating appliance for platen presses comprising a bar carried by the gripper carriage, and a scoring or perforating blade attachable to either side 45 of such bar.

2. A scoring and perforating appliance for platen presses comprising a bar carried

by the gripper carriage, and a scoring or perforating blade removably attachable to either side of such bar.

3. A scoring and perforating appliance for platen presses comprising a bar applied to the face of the platen, scoring and perforating blades carried by the bar, a basal enlargement of said bar applied to the face 55 of the gripper carriage, and adjustable devices carried by said enlargement and co-operating with said gripper carriage whereby to secure the angle and lateral position of the bar.

4. A scoring and perforating appliance for platen presses comprising a bar applied to the face of the platen, scoring and perforating blades carried by the bar, a basal enlargement of said bar applied to the face 65 of the gripper carriage, and adjustable bolts and nuts carried by said enlargement and co-operating with the slots in the gripper carriage whereby to secure the angle and lateral position of the bar.

5. A scoring and perforating appliance for platen presses comprising laterally spaced bars applied to the face of the platen, scoring and perforating blades carried by the bars, supports for the lower ends of the 75 bars, and adjustable devices carried by the bars near their upper ends to secure them in suitably-spaced relation.

6. A scoring and perforating appliance for platen presses comprising laterally spaced bars applied to the face of the platen, scoring and perforating blades carried by the bars, a basal enlargement of each bar applied to the face of the gripper carriage, adjustable devices carried by the bars near 80 their upper ends to secure them in suitably-spaced relation, and other adjustable devices carried by the enlargement of each bar whereby to secure the angle and lateral position of such bar.

In testimony whereof I affix my signature.

MORRIS TEPPER.
